UNITED STATES PATENT OFFICE.

JESSE M. CLOCK, OF NEW YORK, N. Y.

REFRIGERATOR.

SPECIFICATION forming part of Letters Patent No. 274,276, dated March 20, 1883.

Application filed April 7, 1882. (No model.)

To all whom it may concern:

Be it known that I, JESSE M. CLOCK, of the city, county, and State of New York, have invented certain new and useful Improvements in Refrigerators, of which the following is a specification.

My invention aims to take advantage of the low temperature and non-conducting property existing in the shaded earth—such as that below cellar-floors—in order to construct a refrigerator which shall be both very efficient in its cooling power and at the same time very economical in the use of ice.

To this end the main feature of my invention consists in a refrigerator constructed with an ice or cooling chamber embedded in the earth below cellar-floors or similar situations, with an inclosed shaft or casing rising therefrom to a convenient height, preferably to the floor above, and provided with suitable doors for access, and with a movable food-receptacle arranged to move up and down in the same, whereby the receptacle may be raised to a convenient level for the reception or removal of provisions, and thence lowered into the ice or cooling chamber below the ground, by which construction a very efficient and economical refrigerator is produced, which is also very convenient in its location and operation.

My invention also consists in a number of subordinate features, as hereinafter fully set forth.

In the drawings annexed, Figure 1 presents a central vertical section of my improved refrigerator. Fig. 2 is a sectional plan on the line xx of Fig. 1. Fig. 3 is a sectional front elevation of the upper part. Fig. 4 is a sectional plan on line yy , and Fig. 5 illustrates a detail.

In Fig. 1, a indicates the surface of the earth, or, in the case illustrated, represents the cellar-floor of a house, while b indicates the side wall, and c the basement-floor. d e indicate the refrigerating-chamber or essential portion of my improved refrigerator, which, according to my invention, is sunk or embedded in the earth below the cellar-floor, and is, for convenience, divided into two chambers, d e . The lower chamber, d , which is in the extreme base of the refrigerator, forms the ice-chamber or the receptacle for the cooling medium, while the chamber e , immediately over the ice-cham-

ber, forms the cold-air chamber, in which a movable receptacle containing provisions or other articles to be cooled may be lowered, so as to rest directly over the ice. The cold-air chamber rises a little above the ground or cellar-floor, as shown in Fig. 1, and from the top of the cold-air chamber, which is indicated by the annular ledge e' , a close casing or shaft, g , rises in line with the refrigerating-chambers d e , and, passing through the basement-floor c , opens into a closet, f , erected around the shaft upon the basement-floor and rising to a convenient height therefrom, as fully illustrated in Fig. 1. This closet f is provided with a convenient door, f' , on its front, to permit easy access to the shaft and close the approach thereto as occasion requires. The casing g is also provided with a door, g' , of proper size, arranged just above the ledge e' , around the top of the cold-air chamber, to admit of inserting the ice in the ice-chamber below, or of allowing the necessary access to clean the interior or arrange its contents, as will be readily understood. The closet f is preferably made square in cross-section, as seen in Fig. 2, and the shaft and refrigerating-chamber circular, and I prefer to construct the closet of wood and the shaft and refrigerating-chamber of brick or hydraulic cement; but any other suitable shapes or materials may of course be adopted.

The bottom of the ice-chamber d is made slightly concave or inclining toward the center, from which a waste-pipe, d'' , is led to carry off the water resulting from the melting of the ice. Now, from the top of the closet f a metal hanger, i , depends and terminates with a ring, k , as seen best in Figs. 1 and 3, in which three rods, l , are fixed, which rods are arranged in a triangular cluster and extended centrally down through the shaft g and cold-air chamber e , and are fixed at the bottom ends in a disk, m , of metal or hard wood, from which disk a cross, m' , of four radial arms extend and rest on an annular ledge, d' , which indicates the division between the ice-chamber and cold-air chamber, as fully shown in Figs. 1 and 4. Between and on the arms of the cross m' segments n , of sheet-zinc or other suitable material, are placed or socketed, as shown well in Figs. 1 and 4, one or more of which segments may be readily removed when desired to insert ice in the ice-

chamber or to clean the interior thereof, as will be understood. The cross m' , with its segments n , thus form a partition between the ice and cold-air chambers, while the rods l form a central guide over which the movable food receptacle or carrier p may be run up or down, and between which is guided a counterbalance-weight, o , which is connected with the food-carrier by cords r , running over a pulley, s , at the top of the closet, as illustrated in Fig. 1. The carrier, as shown in Figs. 1 and 3, consists of a central cylinder, 2 , which slides over the rods l and the top and bottom heads, 3 and 4 , which are joined at the center by the cylinder 2 and at the circumference by upright slats 5 , the spaces between which allow of placing articles in or removing them from the carrier, as will be understood. The carrier is preferably made of sheet metal, with the exception of the bottom head, which is preferably of wood perforated to allow free circulation of the cold air, and one or more shelves of perforated wood or metal may be placed in brackets 6 , projecting from the slats 5 , between the upper and lower heads, as shown in Fig. 1. The upper head, 3 , is provided with a projecting rim, 7 , which is adapted to rest on the ledge e' , and thus form a sufficiently tight joint to confine the cold within the carrier and prevent any wasteful escape of cold air, as will be understood. A bar or flange, 8 , extends across the upper head, 3 , to stiffen the same, and the ends of the two suspending cords or chains r , as seen in Figs. 1 and 2, are connected thereto, which cords pass up on the outside of the guide-rods l , thence run over the outside of the pulley, and their opposite ends run down from the center of the pulley through the ring k and connect with the counter-weight between the rods s , as shown in Fig. 1. The pulley-block, as shown best in Fig. 5, also in Figs. 1, 2, and 3, is provided with two sheaves—one for each cord—pivoted eccentric to each other, as seen in Fig. 5, by which arrangement one end of each of the two cords run clear of each other on the outside of the guide-rods and the other ends run clear of each other on the inside of the guide-rods, as will be understood. It will therefore be seen that, by this suspended and counterbalance arrangement of the carrier in the refrigerator, by pulling the cords r one way or the other, the carrier may be easily run up or down in the refrigerator, so that if the carrier is lowered to its refrigerating position in the base or cooling chamber of the refrigerator, as shown by full lines in Fig. 1, it may, when required, by opening the closet-door f' and seizing the cords r , be readily raised to a level with the closet-door, as indicated by dotted lines, thus allowing any article to be conveniently placed in or removed from the carrier, after which the carrier can be again lowered into the cooling-chamber. Hence by this means, while the refrigerating-chamber is in the cool cellar, the carrier or food-receptacle is brought into convenient reach on the basement-floor without the necessity of going into

the cellar, and the important advantage is obtained that the refrigerating-chamber is sunk or embedded in the earth below the cellar-floor, where the temperature is of course always much less than the atmosphere, and which is always a great non-conductor of heat, so that an efficient cooling effect is thus obtained and great economy in the use of ice is accomplished. For example, I find that the temperature of the earth below the cellar-bottom is on the average of from 30° to 40° less than the outer air in summer, which very important difference I take advantage of in my refrigerator, and I find by actual experiment that where twenty pounds of ice inclosed in an ordinary refrigerator placed in one of the upper rooms of a house, where the atmospheric temperature was 60° to 65° , would last three days, the same amount of ice placed in my refrigerator, eighteen inches below the earth of the cellar-floor, where the temperature was found to be 39° , lasted nine days, the temperature of the air in the cellar being at the same time 45° , thus showing a great saving of ice. In fact, when the temperature of the earth is low, or where the cellar is very cool, and where much cooling is not desired, the use of ice may be dispensed with during a great part of the time in which it is necessary in ordinary refrigerators, for the earth will in my improved refrigerator furnish sufficient cold, where a good deep and cold cellar is available for its location. In houses which can have no cellar on account of springs near the surface, the base of my improved refrigerator may then be sunk in the spring-water or springing earth to any desired depth, the waste-pipe d'' being of course closed or led to a lower level than the rise of the springs, as will be understood.

Referring to Figs. 5, 3, and 1, it will be noted that the pulley-block is provided with pintles z at top and bottom, which pivot in the hanger i , and thus allow the pulley, as well as the suspended carrier, to be turned horizontally or rotated about half a revolution one way or the other, thereby permitting the carrier to be sufficiently rotated when raised in front of the closet-door so as to bring all sides of the carrier within easy reach. When the carriage is raised into top of the closet it may be there held in front of the door while the articles are being inserted or removed by allowing a spring-tongue, t , projecting from the carrier to catch over the ring k , and there locking the tongue by inserting the key u in the slot in the head through which the tongue projects. When it is desired to lower the carrier the key may be removed, thus allowing the catch to become disengaged, as will be understood.

The weight o should be about equal to the carrier with its average load, and when the load is less than the average movable weights may be placed in the head of the carrier, so that the rim 7 will remain firmly seated on the ledge e' when the carrier is lowered, as will be appreciated.

In some cases it may be desirable to have

the refrigerating-chamber above the cellar-floor, the construction being otherwise the same as shown in Fig. 1, which will of course secure many of the advantages of my invention and obtain a cool place or surrounding for the refrigerating-chamber—viz., the air of the cellar—but not of course as cool as if embedded in the earth below the floor.

What I claim is—

1. In a refrigerator, the food-receptacle *p*, formed as described, and provided with a hollow shaft, through which rods *l* freely pass, said receptacle adapted to move vertically and turn horizontally on said guide-rods *l*, substantially as shown and specified.
2. In a refrigerating structure, the combination of a series of central guide-rods forming upon their inside guides for the central fluted weight, *o*, and upon their outside guides for the surrounding movable food-receptacle, with the connecting-ropes *r* and pulleys *s*, substantially as and for the purpose set forth.
3. The combination, with a cellar-floor or similar earthy bed, of the refrigerating-chambers *d e*, placed in or on the same, the casing *g*, ris-

ing therefrom through the basement-floor, each section inwardly enlarged, for the purpose described, and closet *f*, erected around the same, with a door, *f'*, in said closet above said floor, and a second door, *g'*, in said casing *g* above the cellar-floor, with a movable food-receptacle arranged to run up and down in the refrigerator from said closet-door to the refrigerating-chamber in the cellar, substantially as herein shown and described.

4. The combination, with a refrigerating-chamber having inwardly-sloping bottom with central orifice placed on or in the floor of the cellar, of a shaft or casing rising therefrom, a movable tubular food-carrier arranged to run up and down thereon, with central guides, around which said tubular food-carrier runs, and a central counter-balance moving inwardly against said guides, from which the carrier is suspended, substantially as herein shown and described.
